UNITED STATES PATENT OFFICE.

WILLIAM S. AMBERSON, OF WAYNESBORO, PENNSYLVANIA.

GRINDING MACHINE.

Application filed January 22, 1924. Serial No. 687,827.

To all whom it may concern:

Be it known that I, WILLIAM S. AMBERSON, a citizen of the United States, residing at Waynesboro, in the county of Franklin and State of Pennsylvania, have invented new and useful Improvements in Grinding Machines, of which the following is a specification.

This invention relates to an apparatus for grinding cylinders and the like, the general object of the invention being to provide means for revolving the grinding tool and feeding it longitudinally simultaneously and for rotating the cylinder to be ground so that the grinding tool will come in contact with all parts of the cylinder surface to be ground.

Another object of the invention is to provide means for moving the tool carrying part horizontally at the end of each vertical stroke of the tool so that the tool will grind deeper into the wall of the cylinder in its new vertical movement.

A further object of the invention is to provide means for automatically causing the longitudinal movement of the grinding tool to be reversed at certain points in its downward and upward movement.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a side view of the apparatus.

Figure 2 is a plan view.

Figure 3 is a longitudinal sectional view.

Figure 4 is a section on line 4—4 of Figure 1.

Figure 5 is an enlarged elevation of the hand lever and the parts associated therewith for operating the clutch of the worm shaft.

Figure 6 is a section on line 6—6 of Figure 3 with parts removed.

Figure 7 is a section on line 7—7 of Figure 6.

Figure 8 is a section on line 8—8 of Figure 4.

Figure 9 is a side view with parts in section of the parts shown in Figure 8.

Figure 10 is a sectional detail view of the spring means for moving the worm shaft clutch.

In these views, 1 indicates a base upon which is mounted the cylindrical support 2 for the turn-table 3 and the housing 4 upon which is supported the upright 5 and which carries the bearings for the lower end of the screw shaft 6, the upper end of this shaft being supported by the arm 7 which is carried by the upright. A frame 8 is rotatably connected at one end with the upper end of the support and an arm 9 is slidably mounted on the support, this arm carrying a nut 10 which engages the screw shaft 6 so that when the shaft is rotated the arm will be raised and lowered on the support. The tool carrying shaft 11 is formed of two portions which are connected together in the head 12 which is slidably mounted on the enlarged outer end 13 of the arm 9 which is of arc shape so that the head will travel in an arc of a circle. The upper end of this shaft passes through the outer end of the frame 8 and has a gear 14 slidably but non-rotatably mounted thereon, the gear being held against sliding movement by a weight 15 on the upper end of the shaft. The tool is shown at 16 on the lower end of the shaft. These parts will permit the shaft 11 and the tool to be moved vertically when the arm 9 is moved on the upright by the shaft 6. The tool shaft can also be moved in an arc of a circle by moving the head 12 on the enlargement 13 by means of the hand wheel 17 which has a threaded part for engaging a screw shaft 18 which has its bearing 19 swiveled to a bracket 20 secured to one end of the enlargement 13 and the inner end of the screw shaft is pivoted to the head, as shown at 21. When the head is given this horizontal movement the frame 8 will also be given a horizontal movement by the shaft 11. This will permit the tool to be brought against the wall of a cylinder being ground. The gear 14 is in mesh with a gear 22 fastened to the stub shaft 23 carried by the frame 8 and which is connected by the beveled gears 24

with the shaft 25 carried by the frame 8 and which is connected by the bevel gears 26 with the the shaft 27 which is journaled in the upright 5. This shaft 27 is geared to a shaft 28 by the gears 29, the shaft 28 being arranged in the housing 4 and being connected by the gears 30 with a shaft 31 which passes through the housing and into the support 2 where its pinion 32 meshes with a worm gear 33 on the bottom of the turntable 3. This shaft 31 is driven from any suitable source of power through means of the gear 34. Clutch gears 35 are slidably mounted on the shaft 28 and are arranged to engage a gear 36 on the lower end of the screw shaft 6 so that the said screw shaft can be rotated in one direction or the other from the shaft 28. The clutch gears can be shifted by means of a hand lever 37 which is connected with the outer end of the shaft 38 journaled in the housing and to which the yoke part 39 of a bell crank 4 is connected, this yoke part engaging a groove in the connecting part of the clutch gears. I also provide means for automatically shifting the gears when the arm 9 reaches the upper and lower limits of its movement, such means consisting of a rod 41 connected with the bell crank 40 and passing through the housing and through a sleeve 42 which is provided with the collars 43. This sleeve passes through a notched extension 44 on the arm 9 which is adapted to engage the collars 43 and thus move the sleeve vertically. Springs 45 are placed on the rod 41, one above the sleeve and one below the same and the ends of these springs engage the collars 43 and the projections 46 on the rod so that the springs will be compressed by the movement of the sleeve and will thus tend to move the rod to shift the clutch gears through means of the bell crank. In order to store up energy in the springs to snap the gears into mesh with the gear 36 I provide a pair of spring plungers 47 which operate in cylinders 48 on an arc member 49 carried by the casing 4 and which engage the depressions 50 in the hand lever and tend to hold the hand lever in its limits of movement and thus prevent movement of the clutch parts by the springs 45. A cam 51, carried by a lever 52, pivoted to the shaft 38, is arranged to engage a roller 53 on each plunger so as to draw the plunger from the recess and thus permit the shifting of the hand lever and the clutch parts by the springs. A lever 54 is connected with the lever 52 and has a counter-balanced weight 55 at one end thereof and its other end is connected with a rod 56 which has its upper end passing through holes formed in arms 57 on the collars 43 and connected to said arms by set screws so that said rod will move the sleeve 42 and thus cause the lever 54 to swing the arm 52 in one direction or the other and cause the cam 51 to engage the

roller on the plunger to release the plunger from the recess in the handle and thus permit the stored up energy in the spring 45 to act on the clutch parts through the rod 41. These parts are so arranged that the sleeve 70 42 is moved to a considerable extent to store up energy in the spring 45 before the rod 56 is moved sufficiently to cause the cam 51 to operate the plunger to retract the same. This action will cause the clutch gears to be 75 snapped into mesh with the gear 56.

I also provide means for automatically moving the head 12 in an arc of a circle to adjust the tool against the wall of a cylinder block. Such means consists of a ratchet wheel 59 formed on the hub of the wheel 17 and a pawl 60 carried by a lever 61 pivoted to the shaft so that the pawl will engage the ratchet wheel. A link 62 connects the lever 61 with an arm 63 pivoted intermediate its ends and which is in turn connected by a link 64 with a similar arm 65 which is normally held in neutral position by the springs 66. This arm 65 is adapted to be rocked in one direction or the other by the vertical movement of the arm 9 by means of the rollers 67 on the brackets 68 carried by the rod 56 so that as the arm 9 nears the limit of its movement in either direction a roller 67 will strike the lever 65 and thus rock the same and this rocking movement is communicated to the arm 63 and through this arm to the ratchet mechanism so that the wheel 17 is turned. This turning movement of the wheel will cause the threaded shaft 18 to be moved longitudinally and thus the frame 8 and head 12 will be moved horizontally to cause the tool to be moved against the wall of the cylinder block.

From the foregoing it will be seen that the 105 tool shaft is rotated from the shaft 28 through the gears and shafting mentioned, the tool is given a reciprocatory motion by the worm shaft 6 and its associated parts so that it will engage the length of the cylinder 110 wall while the cylinder is being rotated by the turntable and the tool at each end of its vertical movement is moved slightly in a horizontal plane so that it will grind deeper into the wall in its new vertical movement. 115 The movements are all automatic so that the device needs but slight attention.

I provide holding jaws 69 for holding the cylinder block, as shown at A in dotted lines in Figure 3, in the turn-table, these holding 120 members operating in radial grooves in the turntable and being adjusted by the screw shafts 70 carried by the turntable and having their outer ends formed to fit a suitable wrench, as shown at 71. I may also provide 125 a hose 72 for supplying water or the like to the surface being ground.

I also wish it to be understood that my improved grinding machine may be used for grinding one or more cylinders simulta- 130

neously and when a multiplicity of cylinders are being ground I contemplate making such changes in the grinding machine as to adapt the machine to the number of cylinders to be acted on.

It is thought from the foregoing description that the advantages and novel features of my invention will be readily apparent.

I desire it to be understood that I may 10 make changes in the construction and in the combination and arrangement of the several parts, provided that such changes fall within the scope of the appended claims.

What I claim is:

- 15 1. A device of the class described comprising a work holder, means for rotating the same, an upright, an arm slidably mounted thereon, a head movable on the outer end of the arm in an arc of a circle, a frame rotatably connected with the upright and arranged over the arm and head, a shaft carried by the head and having its upper end slidably mounted in the outer end of the frame, gears and shafting carried by the 20 frame for rotating the shaft, a tool carried by the shaft, a screw shaft, a nut on the arm engaging the same for moving the arm vertically, a drive shaft, means for transmitting the movement of the same to the 25 driving means on the frame, gearing including clutch gears for connecting the drive shaft with the screw shaft, a rod connected with the clutch gears for shifting the same, springs on the rod, a member engaging the 30 springs and actuated by the reciprocatory movement of the arm for tensioning the springs, means for preventing movement of the rod, means for releasing said means when the springs are under their greatest 35 tension whereby the stored up energy in the springs through the medium of the rods will snap the clutch gears into mesh.

- 40 2. A device of the class described comprising a work holder, means for rotating the same, an upright, an arm slidably mounted thereon, a head movable on the outer end of the arm in an arc of a circle, a frame rotatably connected with the upright and arranged over the arm and head, a shaft 45 carried by the head and having its upper end slidably mounted in the outer end of the frame, gears and shafting carried by the frame for rotating the shaft, a tool carried by the shaft, a screw shaft, a nut on the arm 50 engaging the same for moving the arm vertically, a drive shaft, means for transmitting the movement of the same to the driving means on the frame, gearing including clutch gears for connecting the drive shaft 55 with the screw shaft, a rod connected with the clutch gears for shifting the same, springs on the rod, a member engaging the springs and actuated by the reciprocatory 60 movement of the arm for tensioning the 65 springs, means for preventing movement of the rod, means for releasing said means when the springs are under their greatest tension whereby the stored up energy in the 70 springs through the medium of the rods will snap the clutch gears into mesh.

the rod until the parts of said means are in a certain position so that the stored up energy in the springs will snap the clutch gears into mesh through the medium of the rod and a hand lever for shifting the clutch 70 gears.

3. A device of the class described comprising a work holder, means for rotating the same, an upright, an arm slidably mounted thereon, a head movable on the outer end of the arm in an arc of a circle, a frame rotatably connected with the upright and arranged over the arm and head, a shaft carried by the head and having its upper end slidably mounted in the outer end of the frame, gears and shafting carried by the frame for rotating the shaft, a tool carried by the shaft, a screw shaft, a nut on the arm engaging the same for moving the arm vertically, a drive shaft, means for transmitting the movement of the same to the driving means on the frame, gearing including clutch gears for connecting the drive shaft with the screw shaft, a rod connected with the clutch gears for shifting the 80 same, springs on the rod, a member engaging the springs and actuated by the reciprocatory movement of the arm for tensioning the springs, means for preventing movement of the rod until the parts of said means are in a certain position so that the stored up energy in the springs will snap the clutch gears into mesh through the medium of the rod and means actuated by the reciprocatory movement of the arm for 85 automatically moving the parts in an arc of a circle to keep the tool against the surface being operated upon.

4. An apparatus of the class described comprising a turn-table, jaws adjustably mounted thereon for gripping the work-piece, an upright, an arm slidably mounted thereon, a head adjustably mounted on the arm, a tool shaft passing through the head, a tool connected with the lower end of the 105 shaft, a member rotatably connected with the upper end of the upright, a gear thereon keyed to the tool shaft so that the shaft can slide through the same, a shaft passing through the upright, means for driving the gear from said shaft, such means being carried by the member, a screw shaft connected with the arm for moving the same upon the upright, and means for rotating the screw 110 shaft, the shaft in the upright and the turn-table.

5. An apparatus of the class described comprising a turn-table, jaws adjustably mounted thereon for gripping the work-piece, an upright, an arm slidably mounted thereon, a head adjustably mounted on the arm, a tool shaft passing through the head, a tool connected with the lower end of the shaft, a member rotatably connected with the upper end of the upright, a gear thereon 115

keyed to the tool shaft so that the shaft can slide through the same, a shaft passing through the upright, means for driving the gear from said shaft, such means being carried by the member, a screw shaft connected with the arm for moving the same upon the upright, means for rotating the screw shaft,

the shaft in the upright and the turn-table and automatic means for reversing the movement of the screw shaft when the arm reaches certain positions on its upward and downward movements.

In testimony whereof I affix my signature.

WILLIAM S. AMBERSON.
